HEAT TRANSFER APPARATUS AND METHOD
OF MANUFACTURE

Perry R. Cassidy, Darien, Conn., assignor to The Babcock & Wilcox Company, Jersey City, N. J., a corporation of New Jersey

Application June 3, 1942, Serial No. 445,588

11 Claims. (Cl. 122—235)

1

The invention herein disclosed relates to heat exchange apparatus particularly adapted to the transfer of heat between fluids through the wall of a metallic tubular element.

When heat is to be transferred from a fluid outside of a tube to a fluid inside of a tube, or vice versa, there is a resistance to the flow of heat at the boundary of each fluid and in the material of the tube, the cumulative effect of these thermal resistances determining the heat transfer rate for a given temperature excess of one fluid over the other. In many cases of practical importance, heat is transferred from a gaseous fluid outside of the tube to a liquid within the tube, the liquid remaining as such or boiling to a vapor; and under these conditions, the boundary of gas outside of the tube affords a much greater resistance to heat flow than the tube metal and inside fluid boundary combined, and acts to control and limit the rate of heat transfer.

Therefore, when the controlling thermal resistance is in the boundary of a gas outside of a tube, and it is desired to increase the rate of heat transfer, it is common practice to increase the external surface area of the tube, and thus the gas boundary area, by providing metallic extensions on the outside of the tube in the form of fins, studs or pins; the manner of constructing such extended surface units generally involving the attachment of a solid piece of metal to the tube by means of a pressure joint or by the continuous metallic juncture such as results from soldering, brazing or welding.

When fluid carrying tubes are used in the walls of furnaces as outside boundaries or partitions, especially those of steam boilers, they are commonly spaced apart in a row with their ends similarly spaced and suitably connected to headers for the desired ligament strength. The spaces between such wall tubes have generally been closed by metallic extensions on individual tubes, with or without the addition of refractory material, to provide an exposed surface bridging the space between tubes from which surface heat is conducted through the extension metal to the metal of the tube and thence to the fluid within the tube.

A purpose of the present invention is to provide a heat exchange unit especially adapted to the transfer of heat between fluids of different temperatures, one fluid being carried within a metallic tubular member and the exterior surface of the member being extended to provide increased area of exposure to the other fluid. Certain particular embodiments of the invention are

2

contemplated whereby a plurality of such units may be disposed in the path of a moving fluid, either gaseous or liquid, with the entire extension surface swept by the moving fluid at minimum resistance to the flow of such fluid. Other embodiments utilizing different forms of extensions may conveniently be arranged to form an impervious wall structure, associated with a furnace for example, where ordinarily only a portion of the extension surface is exposed directly to a source of heat.

For any condition of service, the arrangement of the extension is such that heat received at its exposed outer surface, for example, is conducted through the material of the extension to its juncture with the tubular member without excessive temperature differential between the extreme outermost portion of the extension and its innermost portion or root. This involves suitable attachment of the extension to the tubular base portion to provide thermal contact of sufficient area and conductivity to avoid overheating the part farthest from the tube, the attachment being also made in such manner as to prevent excessive stresses being set up in the tube due to differential thermal expansion and contraction of the metal of the tube and that of the extension.

In the furtherance of these objects it is proposed to provide a composite form of extension wherein different materials are combined, both of which are conductors of heat but usually in different degrees, with one more refractory to heat and serving as a shield or jacket for the other.

In most instances, it will probably be found most suitable to form the outer shield or jacket of relatively thin metal, the selection of the kind of metal being determined in part by the character of service for which the heat exchange unit is intended, and in part by its cost. Accordingly it is desirable to form the sheath or jacket of a metal of relatively high resistance to corrosion, with reference to the temperatures, and to the character of fluid, to which it may be exposed.

The other portion of the composite extension is disposed between the metal shield or jacket and the metal of the tubular member as a heat transfer medium, for the transfer of heat from the jacket to the tubular member or from the tubular member to the jacket depending on the relative temperatures inside and outside of the tubular member as affecting the direction of heat flow. As a heat transfer medium it is proposed to use a material different from that of the sheet metal jacket, selected for ease or economy of applica-

tion, and of suitable heat carrying capacity for the temperature conditions under which it must function in service.

The filler material may be solid at ordinary temperatures and remain solid during operation at higher temperatures, metallic or non-metallic, and may be shaped to fit the jacket and the tube before the jacket is attached to the tube, or it may be molten and poured into the jacket space after the jacket is attached to the tube. It may have metallic fusion or alloy attachment to the jacket, or to both jacket and tube, according to conditions of cost in relation to thermal carrying capacity. For example, a sheet steel jacket, with copper filling would be suitable for steel tube water walls, the copper being fitted as a solid block or poured molten.

The filler material may be solid at ordinary temperatures and become molten during operation at higher temperatures, and metallic such as lead, or non-metallic, organic or inorganic, including diphenyl and such substances known as bath salts for immersion heat treatment of metals to and at a given high temperature.

The filler material may be liquid at ordinary temperatures and remain liquid during operation at higher or lower temperatures, such as mercury for example, or an oil, or for very low temperatures a brine.

The filler material may be liquid at ordinary temperatures and freeze to a solid during operation at lower temperatures or boil to a vapor during operation at higher temperatures.

The filler material may also be composite, for example, a liquid in which solid particles are submerged, the liquid being any one of the liquid media heretofore described and the solids having generally a higher thermal conductivity as in the case of metals, especially copper and aluminum, and preferably being in such form as to provide a compact mass with relatively little liquid between the solid particles when the jacket space is filled. Solids for this purpose include metal balls, or metals in granular form such as filings or cutting tool chips, or non-granular particles of metals that cutting tools do not chip. Such metallic or even non-metallic solid particles of greater conductivity than that of the liquid around them increase the heat carrying capacity of the jacket filler over that of liquid alone. It is less than for a filling of the same metal alone but cheaper and easier to apply.

The difference in the materials of the sheet metal jacket and its filler, results in differences in physical properties including that of thermal expansion, and in addition, their relative positions result in differences in temperature, mean and actual local values. My construction makes it possible to avoid damage due to such differences and in some cases to advantageously utilize the differences.

When the filler is a material that remains solid in operation, and the heat flow is inward, the filler material may be selected to have a sufficiently higher coefficient of thermal expansion than that of the jacket so that in spite of a lower mean temperature, it will expand more than the jacket and insure close contact between the filler and tube on one side and between the filler and jacket elsewhere for good thermal conduction and without imposing excess stresses. On the contrary, when the heat flow is outward, and the mean temperature of the filler is higher than that of the jacket, a different material may be used with the same or a lower coefficient of ex-

15 pansion to the same end. To avoid excess stresses without compensating coefficients of expansion the sheet metal jacket may be so formed as to yield under stresses within the elastic limit.

When a liquid is used as the filler and it remains liquid, or when a solid is used that becomes liquid, in operation, the expansion and contraction conditions may be met, by forming the sheet metal jacket so that it yields to changes in the volume of the filler while keeping its metal stress within the elastic limit. Also, a space may be left unfilled above the liquid to reduce the maximum pressure exerted by the filler at its highest temperature excess over that of the jacket, when thermal conditions are such as will not overheat the jacket around the unfilled space.

With a filler that is liquid in operation the heat transfer between the tube and the jacket is not limited to pure conduction as is the case of a solid filler, or packed solid particles submerged in a liquid, because convection circulation is set up in the liquid causing upward flow next to the hotter metal face and downward flow next to the colder one, to carry the heat in the moving liquid from the hotter to the colder face. The jacket may also be formed so as to be flexible to limit internal pressures.

A filler material that vaporizes during operation, a liquid that boils, or a solid that sublimes, also conducts heat from a hotter to a colder face of its enclosure, the vapor forming on the hotter face and condensing on the colder face. A space above the liquid may preferably be left in this case to limit maximum pressures and for the same purpose the jacket form may be a yielding one.

Those skilled in the art are referred to the accompanying drawing for a more detailed disclosure of the manner in which the invention may be utilized in certain specific forms for various conditions of service. The embodiments shown have been selected by way of example and with a view to illustrating a number of different constructions which may be followed in the practice of this invention. These embodiments it will be noted are of simple construction, thus facilitating manufacture of the apparatus and contributing to low cost of production either in small or large quantities. The method of their manufacture is also pertinent to the installation and/or replacement of such apparatus in the field, the latter being a factor of considerable importance in reducing the time required for restoring normal operating conditions, particularly when the installation is remote from the place of original manufacture.

The accompanying drawing, and the structures shown therein, may be briefly described as follows:

60 Fig. 1, in sectional elevation, shows a steam boiler unit embodying certain features of the invention;

Fig. 2 is a fragmentary transverse section along line 2—2, for example, of Fig. 1;

Fig. 3 is a front elevation of parts shown in Fig. 2;

Figs. 4 and 5 are fragmentary transverse sections similar to Fig. 2 showing modifications;

Fig. 6 is a fragmentary transverse section along line 6—6, for example, utilizing parts shown in Fig. 2; and

Fig. 7 shows an additional modified form of the invention, in section along line 7—7, for example, of Fig. 1.

In detail, the boiler unit of Fig. 1 includes a

combustion chamber A represented as being fired with pulverized fuel burners B and defined by walls C, each of which is illustrative of an embodiment utilizing fluid cooling elements constructed and arranged as more specifically described hereinafter. The hot gaseous products of combustion resulting from the combustion of fuel within the chamber A are discharged through the opening D formed between spaced fluid cooling elements of the inner wall C' which partitions the combustion chamber A from the upflow open gas pass E, the gases continuing in their flow through the opening F above the upper end of a second fluid cooled partition wall G downwardly through a second open gas pass H disposed between the fluid cooled walls G and K. Gases leaving the lower portion of pass H are directed across a row of spaced tubes 10 and thence upwardly through the gas passage M across other rows of spaced fluid heating tubes forming, for example, the superheater 12, economizer 14 and boiler section 16. In the arrangement shown, all of the fluid cooling elements associated with the combustion chamber A and with the gas passes E and H are so constructed and arranged as to constitute a considerable portion of the boiler heating surface available for the generation of steam or other vapor.

The walls 18, 20 and 22 constituting outer boundaries of the furnace chamber A may be constructed as shown in Figs. 2 and 3 to include a plurality of wall cooling elements 24 arranged at suitable spacings in a row across the width of the wall, each element comprising a tubular member 26 having its ends suitably connected to headers 28 and 30, for example, for the circulation of boiler fluid therethrough. Each wall element 24 is preferably compositely formed to provide a greater area of exterior surface than is afforded by the tubular base member 26.

As shown in Fig. 2, for an outer furnace wall 18, for example, a plurality of extensions 32 may be secured to each tubular member 26 in symmetrical arrangement to provide a substantially continuous planar surface 34 offset from the center line of the row, preferably in substantially tangential relation to the convex outer surfaces of the tubes 26. A small clearance space 36 may be left between adjacent extensions 32 on adjacent tubes. The spaces to the rear of the extensions may conveniently be filled with a suitable ceramic refractory material 38 applied in a plastic or semi-plastic condition with a suitable backing of heat insulating material 40. Individual extensions 32 can be made in relatively short lengths so that a plurality can be fitted to a single tube length, with a small expansion space 42 between adjacent extensions, as indicated in Fig. 3. Each extension 32 is in itself a composite structure, being formed of an outer metallic portion 44 serving as an enclosure for an inner heat conducting portion 46. For a tube 26 of low carbon steel, of about $3\frac{1}{4}$ " outside diameter, the material of the jacket 44 may also be of low carbon steel, preferably in plate form of about $\frac{1}{8}$ " thickness, and the filler material 46 of copper, as one example of a suitable filler as heretofore described.

If the operating temperatures should be such that a different relationship is desired between the thermal expansion of the jacket and that of the filler, an adjustment could be made by modifying the composition of one or the other of the materials, for example, instead of using a low carbon steel for the jacket as described, an alloy

of steel might be preferable, with a lower or higher coefficient of expansion, as required.

The jacket 44 may be formed as a box with one side open and with edges 48 and 50 at the perimeter of the side opening adapted to be welded to the wall of the tube 26 as shown. Plates 52 forming the ends of the box provide edges 54 at the perimeter of the side opening also for welding to the tube wall. After the box has been formed, from a single plate or from a plurality of plates joined together, the box may be filled with scrap copper, preferably of high purity, and the copper integrally brazed with the inside surface of the box and fused to form a solid block of metal within the box projecting beyond the edges 48, 50, 54 a sufficient distance to allow for machining to a concave surface accurately fitting the outside diameter of the tube 26, the filler material still extending a small distance beyond the welding edges. The contact area of the tube may be thoroughly cleaned, by brushing or by sand-blasting, and the composite extension suitably clamped against the tube in position for welding. The assembly with the tube 26 may be completed by fillet welding along the edges 48, 50, 54 as shown, the slight shrinkage of the welds tending to draw the block of filler material 46 against the tube wall and to maintain close thermal contact throughout the entire area of contact.

It will be noted that the walls of the jacket are relatively thin and of substantially uniform thickness throughout, a thickness not exceeding the thickness of the tube metal generally being sufficient. As seen in Fig. 2, such walls represent a relatively small cross-section of jacket metal in comparison with cross-section of the entire extension, the cross-sectional area of jacket metal being less than the cross-sectional area of the space within the jacket and consequently less than the cross-sectional area of the heat conducting filler.

Various filler materials 40, and methods of application have already been discussed. For example, it has been stated that a metal such as copper could be poured into the box in a molten condition, in which case the box or jacket 44 could be welded to the tube in an upright position, with its upper end open, and the molten copper poured into the box through its open end, whereupon if desired the upper end plate 52 could be welded to the sides of the box and to the tube to complete the assembly. The same general method of procedure may be followed for other molten metals, and for such other materials as have been mentioned of a fluid or semi-fluid character. It will be understood that when the filler material is a solid at ordinary temperatures, a block of the material may be preformed and then assembled with a jacket of conforming contour against the tube, the filler block preferably projecting beyond the edges of the jacket and the jacket edges being welded to the tube as before. The extension 32 is of desirable form in that it presents a smooth surface toward the heating zone and in conjunction with adjacent similar extensions forms a closure for the space between tubes 26 and provides a substantially continuous planar wall surface. The edge portions 48 of the box are bent out of the plane of the surface 34 to provide an angular recess 58 of at least 90° with the wall of the tube 26 to accommodate a deposit of weld metal sufficiently large for strength without forming a projection beyond the plane of the surface 34. The rearward surface 60 of the extension 32 diverges sufficiently from the plane of

the forward surface 34 to form a similar welding recess 62 of at least 90° between the longitudinal edge portions 50 and the tube wall. Thus from its extreme outer edge portion 56 advancing inwardly toward the tube wall, the cross section of extension 32 is expanded so that the filler material 46 engages the tube throughout an arc greater than 30°, with a total arc of engagement of at least 45°, and preferably from about 50° to 60°, for the entire composite extension 32 including the welds along longitudinal edges 48 and 50.

According to Fig. 4, each composite extension 64 presents a planar surface 34 preferably arranged in tangential relation to the exterior wall of tube 26 as in Fig. 2, the edge portions 48, 50 and 54 of the jacketing member 66 being similarly arranged and welded to the tube wall. The rearward portion 68 of the jacket, normally the unheated portion, is formed with one or more bends or corrugations 70 to provide flexibility, such corrugations being also formed if desired in the portion 72 of the jacket on the side adjacent a similar block on the adjacent tube. The pocket 74 formed between complementary corrugations on adjacent blocks may be utilized to retain plastic refractory material for sealing the joint between adjacent blocks. The heat conducting filler 46 may be one of the several materials heretofore described, a material of fluid or semi-fluid consistency being especially suitable because of its ability to yield to whatever form is required by the flexing of the corrugated wall of the jacket 66. A plurality of extended surface elements such as shown in Fig. 4 may be associated in a wall structure, if desired, with suitable refractory and backing materials 38 and 40 applied as in Fig. 2.

In Fig. 5, each composite extension 16 has a jacket portion 78 of exterior form similar to the jacket 44 of Fig. 2, and similarly welded to the tube 26 along edges 48, 50 and 54. In this embodiment, metallic projections 80 are provided within the jacket 78 and secured either to the tube 26, or to the jacket as shown, to project a substantial distance into the mass of filler material 46 as a means of increasing its heat conducting capacity. Such projections 80 in the form of bars or rivets, for example, may be conveniently welded to a selected area of the jacket 78 when made of sheet metal before the jacket is shaped to final form. The elements of Fig. 5 may also be incorporated in a wall structure similar to Figs. 2 and 3, as will be understood.

Fig. 6 illustrates an embodiment utilizing composite extensions 32 to form a wall structure having exposed planar surfaces 34 at opposite sides, suitable for use where heat is applied to both surfaces as in the case of the partition wall C', for example, dividing the combustion chamber A from the adjacent open gas pass E. Individual extensions 32 may be the same as described as for Fig. 2, or may be of the form shown in either Fig. 4 or Fig. 5, with a suitable filler 46 within the jacket 44 as already indicated. With the blocks 32 attached to both faces of the partition wall in this manner, the spaces between oppositely arranged series of blocks 32 may be filled with a suitable refractory cement 38 to provide a seal against gas leakage from one face of the wall to the other.

When the extended surface elements are arranged in a row to form a wall, as in Figs. 2 to 6 inclusive, it will be understood that suitable provision may be made to maintain them in their relative positions, either by tying adjacent tubes together or by tying the tubes to some stationary

structure as in the case of outside boundary walls.

Fig. 7 illustrates compositely formed extended surface elements particularly adapted for the transfer of heat by convection, a suitable application of such elements being in the gas flue M as the tubular heating surface of a unit such as a superheater, reheat or economizer, wherein heat is transferred from a hot gaseous fluid externally of the element to a fluid, either gaseous or liquid, within the tubular base member 84. However, in other instances, the direction of heat flow may be reversed as previously explained from a hot fluid within the tubular member 84 to a cooler fluid, either gaseous or liquid, externally of the element.

Fig. 7 shows tubes 84 spaced apart in a row to provide for fluid flow therebetween, each tube having its exterior surface extended by means of composite extensions 86 each comprising a metal jacket 88 welded to the tube 84 and containing a suitable heat conducting filler 46 in intimate thermal contact with the tube wall. The jacket 88 is generally V-shaped in cross section and may be formed as a box in the manner described for previous embodiments, with the side toward the tube open, and with longitudinal edges 90 and other free edges welded to the tube wall. There may be a plurality of separate extensions 86 along each tube as shown for extensions 32 in Fig. 3. The composite extensions 86 are shown attached to each tube in pairs, at diametrically opposed locations, at the upstream and downstream sides, although other arrangements of a plurality of extensions may be used as well as a single extension circumferentially of each tube. It will be understood also that the tubes in successive rows may be in alignment relative to fluid flow thereover, or may be in staggered relation, as desired.

While in accordance with the provisions of the statutes I have illustrated and described herein the best forms of my invention now known to me, those skilled in the art will understand that changes may be made in the form of the apparatus disclosed without departing from the spirit of the invention covered by my claims, and that certain features of my invention may sometimes be used to advantage without a corresponding use of other features.

I claim:

1. The method of extending the external surface of a tubular element of circular cross section which comprises, forming relatively thin metal into a hollow, box-like jacket having one side open to extend partially around said element, filling the space within said jacket with molten metal to provide a molecular bond between said filler metal and the metal of said jacket, sufficient molten metal being introduced to overfill the jacket space to an extent providing an extension of the filler metal beyond the edges of the jacket surrounding the open side after complete solidification, shaping said filler metal extension to a surface conforming to the external contour of the tubular element, clamping the filled jacket against said tube with the shaped extension surface in contact with the conforming tube wall surface and with the jacket edges spaced therefrom, and welding said jacket edges to the tube wall to maintain close thermal contact between the filler metal and tube.

2. A furnace wall unit comprising a fluid-conducting metal tube having means integral therewith forming extended heating surface for exposure toward said furnace, said means comprising extensions arranged oppositely on said tube

and providing heat absorbing surface substantially in a plane tangent to said tube, each extension being compositely formed to include a sheet metal jacket having oppositely disposed uniformly thin walls in diverging relation toward said tube and terminating in edges spaced circumferentially adjacent said tube through an arc of at least 30°, one of said walls having an exposed surface portion in said plane and having its adjoining inner edge portion bent to extend approximately radially of said tube to form a welding recess below the plane of said exposed jacket surface, filler material within said jacket having a heat transfer capacity greater than the material of said jacket, said filler material having a circumferential dimension of engagement with said tube several times the thickness of said jacket walls and an average circumferential dimension throughout its radial extent also greater than said wall thickness, and means for uniting said edge portions with said tube including weld metal fused within said recess to approximately the tangential position of said exposed heating surface.

3. The method of extending the external surface of a tubular element of circular cross section which comprises, forming relatively thin metal into a hollow box-like jacket having one side open to extend partially around said element, introducing metal in a solid state into the space within said jacket, transforming said metal into a molten mass having fusion engagement with the walls of said jacket, effecting solidification of said mass to provide a block of metal completely filling said jacket space while maintaining its metallic bond with said walls, said filler block providing an exposed surface displaced outwardly from the surrounding edges of said jacket, shaping the exposed surface of said filler block to a surface conforming to the external contour of the tubular element, assembling the filled jacket adjacent said tube with said shaped surface in contact throughout with the adjoining tube wall surface and with said jacket edges spaced therefrom, and welding said jacket edges to the tube wall to maintain close thermal contact between the filler metal and tube.

4. The method of extending the external surface of a tubular element which comprises, forming relatively thin sheet metal of ferrous composition into a box-like jacket having its walls arranged to define an opening in a side thereof adapted to embrace an arcuate area of said tubular element, the space within said jacket being of minimum cross section at a location farthest from said opening and of progressively greater cross section toward its maximum cross section adjacent said opening, effecting solidification of molten metal within said jacket to form a metal filler having a substantially continuous metallic juncture with the walls of said jacket and providing an exposed surface beyond the surrounding jacket edges, said filler metal having a heat conductivity of the order of copper and thereby greater than the heat conductivity of the jacket metal, shaping said exposed surface to a surface conforming to the contour of said arcuate area, positioning said jacket adjacent said tubular element with said shaped surface in contact throughout with said arcuate area and with said jacket edges spaced therefrom, and welding said jacket edges to said tubular member to maintain said metal filler in close thermal engagement with said member.

5. A heat transfer wall unit comprising a fluid-conducting metal tube having means integral

therewith providing extended heat transfer surface, said means comprising extensions arranged oppositely on said tube and providing heat transfer surface substantially in a plane tangent to said tube, each extension being compositely formed to include a sheet metal jacket having oppositely disposed uniformly thin walls in diverging relation toward said tube and terminating in edges spaced circumferentially adjacent said tube, one of said walls having an exposed surface portion in said plane and having its adjoining inner edge portion bent to extend approximately radially of said tube to form a welding recess below the plane of said exposed jacket surface, filler material within said jacket having a heat transfer capacity greater than the material of said jacket, said filler material having a circumferential dimension of engagement with said tube several times the thickness of said jacket walls and an average circumferential dimension throughout its radial extent also greater than said wall thickness, and means for uniting said edge portions with said tube including weld metal fused within said recess to approximately the tangential position of said exposed heat transfer surface.

6. A heat transfer unit comprising a fluid-conducting metal tube having means integral therewith providing extended heat transfer surface, said means comprising an extension on said tube providing heat transfer surface substantially in a plane tangent to said tube, said extension being compositely formed to include a sheet metal jacket having oppositely disposed uniformly thin walls in diverging relation toward said tube and terminating in edges spaced circumferentially adjacent said tube, one of said walls having an exposed surface portion in said plane and having its adjoining inner edge portion bent to extend approximately radially of said tube to form a welding recess below the plane of said exposed jacket surface, filler material within said jacket having a heat transfer capacity greater than the material of said jacket, said filler material having a circumferential dimension of engagement with said tube several times the thickness of said jacket walls and an average circumferential dimension throughout its radial extent also greater than said wall thickness, and means for uniting said edge portions with said tube including weld metal fused within said recess to approximately the tangential position of said exposed heat transfer surface.

7. A heat transfer unit comprising a fluid-conducting metal tube having means integral therewith providing extended heat transfer surface, said means comprising extensions arranged oppositely on said tube and each providing heat transfer surface substantially in a plane tangent to said tube, each extension being compositely formed to include a sheet metal jacket having oppositely disposed uniformly thin walls in diverging relation toward said tube and terminating in edges spaced circumferentially adjacent said tube, one of said walls having an exposed surface portion in said plane and having its adjoining inner edge portion bent to extend approximately radially of said tube to form a welding recess below the plane of said exposed jacket surface, filler material within said jacket having a heat transfer capacity greater than the material of said jacket, said filler material having a circumferential dimension of engagement with said tube several times the thickness of said jacket walls and an average circumferential di-

11

mension throughout its radial extent also greater than said wall thickness, and means for uniting said edge portions with said tube including weld metal fused within said recess to approximately the tangential position of said exposed heat transfer surface.

8. A furnace wall unit comprising a fluid-conducting metal tube having an extension thereon providing extended heat transfer surface substantially in a plane tangent to said tube at the furnace side thereof, said extension comprising a sheet metal jacket formed as a box having one side open and having edges surrounding said open side secured to said tube to define a closed compartment adjacent said tube, the enclosing walls of said compartment thereby including the portion of said tube embraced by said jacket, said jacket having oppositely disposed uniformly thin side walls extending in diverging relation toward said tube and terminating in circumferentially spaced edges adjacent said tube, one of said side walls having an exposed surface portion in said plane and having its adjoining inner edge portion bent to extend approximately radially of said tube to form a welding recess below the plane of said exposed jacket surface, a heat conducting medium fluid at operating temperatures substantially filling said compartment, and heat conducting projections extending into said medium from one of said compartment enclosing walls and terminating in spaced relation with respect to all other said walls, said heat conducting medium having a circumferential dimension of engagement with said tube several times the thickness of said diverging side walls and an average circumferential dimension throughout its radial extent correspondingly greater than said side wall thickness, and means for uniting said edge portion with said tube including weld metal fused within said recess to approximately the tangential position of said exposed heat transfer surface.

9. A heat transfer wall unit comprising a fluid conducting metal tube having an extension thereon providing heat transfer surface substantially in a plane tangent to said tube, said extension comprising a sheet metal jacket formed as a box having one side open and having edges surrounding said open side secured to said tube to define a closed compartment adjacent said tube, and a heat conducting medium fluid at operating temperatures substantially filling said compartment, said jacket having oppositely disposed uniformly thin side walls extending in diverging relation toward said tube and terminating in circumferentially spaced edges adjacent said tube, one of said side walls having an exposed surface portion in said plane and having its adjoining inner edge portion bent to extend approximately radially of said tube to form a welding recess below the plane of said exposed jacket surface, said side wall being formed with projections thereon extending into said medium partially across the space toward the opposite of said walls, said heat conducting medium having a circumferential dimension of engagement with said tube several times the thickness of said diverging side walls and an average circumferential dimension throughout its radial extent correspondingly greater than said side wall thickness, and means for uniting said edge portion with said tube including weld metal fused within said recess to approximately the tan-

12

gential position of said exposed heat transfer surface.

10. A heat transfer wall unit comprising a fluid conducting metal tube having an extension thereon providing heat transfer surface substantially in a plane tangent to said tube, said extension comprising a sheet metal jacket formed as a box having one side open and having edges surrounding said open side secured to said tube to define a closed compartment adjacent said tube, said jacket having oppositely disposed uniformly thin side walls extending in diverging relation toward said tube and terminating in circumferentially spaced edges adjacent said tube, one of said side walls having an exposed surface portion in said plane and having its adjoining inner edge portion bent to extend approximately radially of said tube to form a welding recess below the plane of said exposed jacket surface, the other of said walls having corrugations therein throughout its thickness, a heat conducting medium fluid at operating temperatures substantially filling said compartment, said heat conducting medium having a circumferential dimension of engagement with said tube several times the thickness of said diverging side walls and an average circumferential dimension throughout its radial extent correspondingly greater than said side wall thickness, and means for uniting said edge portion with said tube including weld metal fused within said recess to approximately the tangential position of said exposed heat transfer surface.

11. In a furnace wall adapted for exposure to heating gas zones of different pressures at opposite sides, a row of spaced elongated heat transfer units each comprising a metal tube of curvilinear cross section for conducting fluid to be heated, and means for extending the exterior surfaces of said tubes to provide substantially continuous heat absorbing surfaces in planes substantially tangent to said tubes at opposite sides of said row, said means at each side comprising metal jackets secured in pairs to each of said tubes and a heat conducting material substantially filling said jackets, said jackets each having uniformly thin side walls extending in diverging relation toward one of said tubes and terminating in circumferentially spaced edges adjacent said tube, said jackets having certain of said side walls in said tangent planes for substantially bridging the spaces between adjacent tubes while the remaining side walls diverging therefrom define substantially closed intertube spaces intermediate said planes, one of said walls of each jacket having an exposed surface portion in one of said planes and having its adjoining inner edge portion bent to extend approximately radially of said tube to form a welding recess below the plane of said exposed jacket surface, means for uniting said edge portions with said tubes including weld metal fused within said recesses to approximately the tangential positions of said exposed heat absorbing surfaces, and refractory material filling said intertube spaces for sealing said wall against gas leakage from one of said zones to the other, said heat conducting material having a circumferential dimension of engagement with each tube several times the thickness of said side walls and an average circumferential dimension throughout its radial extent correspondingly greater than said side wall thickness.

PERRY R. CASSIDY.
